COIN HANDLING APPARATUS

William G. Peters, Oak Park, Ill., assignor to
Richard Grotchen, Chicago, Ill.

Application January 11, 1939, Serial No. 250,389

7 Claims. (Cl. 133—2)

This invention relates to a coin handling, storing and discharging receptacle and apparatus. It has for one object to provide a coin carrier or reservoir. It has for another object to provide means for moving that reservoir or carrier so as to discharge a predetermined, variable number of coins or tokens.

Other objects will appear from time to time throughout the specification and the claims.

The device of this invention may be used in many connections. It may, for example, be used in a change-making or token-discharging machine. In the form here shown, it is particularly adapted for that use. It may be used in almost any association in which a movable coin carrier or reservoir is desirable or adaptable for use.

The invention is illustrated more or less diagrammatically in the accompanying drawings, wherein:

Figure 1 is a perspective view of one form of the device with an enclosing housing;

Figure 2 is a vertical, sectional detail on an enlarged scale taken at line 2—2 of Figure 1 with parts of the housing omitted and parts shown;

Figure 3 is a plan view of the coin reservoir or carrier with parts of its driving means and with parts omitted and parts broken away;

Figure 4 is a vertical, sectional detail taken at line 4—4 of Figure 3, illustrating the discharge of a coin or token;

Figure 5 is a vertical, sectional view taken at line 5—5 of Figure 2 on an enlarged scale;

Figure 6 is a vertical, sectional detail taken at line 6—6 of Figure 3;

Figure 7 is an elevation of one of the units used in the construction of the coin carrier;

Figure 8 is a sectional detail taken at line 8—8 of Figure 7.

Like parts are designated by like characters throughout the specification and the drawings.

In general, the mechanism is supported upon and preferably attached to a base member 1. This member may have a downwardly depending flange 2, which serves to strengthen and stiffen it. The particular details of the base member are not important. It will be of such size and strength as to support the parts mounted upon it. It is provided with a raised, hollow boss 3, which serves as a support for the coin carrier. Fixed in the boss 3 is a shaft 4 removably held in position therein by a set screw 5. The shaft may have an enlarged, central section 6, if desired. A washer 7 is positioned about the shaft to rest upon the top of the boss 3. The hub 8

of a lever 9 is positioned about the enlarged portion 6 of the shaft. The shaft may be again reduced as at 10, and it is this portion of the shaft which preferably carries the coin reservoir or carrier. The reservoir includes a hub 11 mounted upon the shaft section 10 for rotation thereabout. A washer 12 may be inserted below the hub, and it will rest in part upon the enlarged shaft section 6. The shaft is reduced and threaded as at 13 to receive a nut 14, which holds the parts in place. The nut may have an integral flange 15, or instead of the flange 15 a washer of the same general size and shape may be used.

15 The hub is provided with a groove 16. Positioned in this groove 16 is a body member 17 generally rounded and provided with a downwardly depending flange 18, which carries an outwardly projecting rack 19. Two other body members 20 and 21, respectively, relatively disc-like in shape, are also received in the groove 16. Each of them is provided with a generally angularly peripheral flange 22, 23. To the peripheral flanges 22 and 23 are secured a number 20 of individual pocket-forming members. As shown in Figures 3 and 5 generally and particularly in Figures 7 and 8, these pocket-forming members comprise pairs of generally rounded members 24 and 25, which are joined by a neck portion 26. Extending from both top and bottom of the neck portion 26 are tongues 27 and 28. In a completed carrier, as shown in Figure 5 and also as suggested in Figure 7, the tongues 27 and 28 are bent about the flanges 23 and 22, respectively. The members 24 and 25 are generally rounded in plan and are cut away as at 29. Along the cut-away portions, they may have one or more inwardly bent, inclined portions or lugs 29a. The members may also be provided with 25 indented ribs 30, 30, and they are preferably provided each with a pair of tongues or lugs 31, 31 of such length that when the pocket-forming members are assembled the tongues of each disc-like member extend to or overlap the edge of 30 an adjacent disc-like member. The effect of this is to provide a means for fastening the edge of each pocket-forming member to its neighbor.

When the coin carrier is assembled as shown in the drawings, it comprises what might be 35 called a "dough-nut" shaped carrier with a series of coin pockets arranged generally on the periphery of the carrier. While this carrier might be used in many associations, the one here shown in a change-making machine will suffice to explain 40 its general utility and method of use.

A guard or enclosing rail 32 is positioned about the carrier and is supported by a bracket-like member 33, which may be secured to it by screws 34 and may be secured to the base 1 by screws 35. A coin-discharge chute 36 is positioned adjacent the coin carrier, and may be enlarged as shown particularly in Figure 3 to provide a portion which may have an edge concentric with the carrier. The discharge chute is reduced and provided with a discharge orifice or delivery member 37, which may terminate in an outlet portion 38. An inlet or feed chute member 39 has an inlet track or passage 40, as shown in Figures 3 and 6, through which coins or tokens are fed to the carrier. The details of this are not shown as the invention is not limited to any particular feed chute construction. At its outer end, it may have a slot into which a coin or token is fed and from which it moves to the passage or track 40, and from which it moves into the carrier. A housing 41 may be provided, and when provided may conveniently serve as a support for parts of the assembly. It may be provided with a transparent window or opening 41a through which the coin carrier is visible.

The means for operating the carrier to cause discharge of coins or tokens will now be described. It is to be understood, however, that this means is merely one example of a means for operating the carrier, and the latter is not limited in its use to this particular association. A stop 42 is secured to the base 1 and extends upwardly as shown particularly in Figures 2, 3 and 5 into the path of the lever 9. The lever 9 carries preferably adjacent its outer end a downwardly projecting pin 43. A dog 44 is pivoted as at 45 upon the lever 9. It carries a point or inwardly bent member 46, which may engage the rack 19. A spring 47, secured at one end to the dog 44 and at the other end to the lever 9, tends to hold the dog in contact with the rack. A second dog 48 is pivoted as at 49 upon a member 50, which extends upwardly from the base 1. A spring 50a is secured at one end to the dog 48 and at the other to a point 51, and tends to hold the dog in contact with the rack 19.

An operating bar or slide 52 is slidably mounted in suitable bearings 53, 54, and carries a handle portion 55, which extends outside of the housing, and by means of which it may be readily moved. An eye 56 secured to the slide 52 loosely surrounds a pin 57, upon which a spring 58 is mounted. At one end, the spring bears against the eye 56, and at the other against a head 59 on the pin 57. A stop member 60 extends upwardly from the slide 52, and serves to limit the movement of the slide in one direction, as will be described below. The slide 52 is provided with a perforation or opening 61, within which the pin 43 of the lever 9 extends. By means of this engagement of the pin 43 in the perforation 61 of the slide 52, movement of the latter is communicated to the lever 9 and through it and the dog 46 and the rack 19 to the coin carrier.

Since in the present mechanism the device comprises a coin or token dispenser, means are provided for inserting coins of several sizes. In the particular form shown, means are provided for receiving dimes, quarters and half dollars, and automatic gauging and limiting means are provided whereby the number of coins or tokens discharged corresponds to the value of the coin inserted. If a dime is inserted, two coins or nickels will be discharged. If a quarter is inserted, five will be discharged; and so on. The coin chute

for entering coins comprises a member 62, which is positioned in part outside of the housing 41. The member 62 is preferably set at an angle with respect to the vertical to assist in ejecting undersized coins through openings described below. It includes an opening 63 for dimes, an opening 64 for quarters and an opening 65 for half dollars. An inclined passage 66 is formed within the member 62. Openings 67, 68 and 69 are formed within the walls of the member 62 to eject under-sized coins. If a quarter is put into the slot 65, it will fall out through the opening 67. If a dime is put in the slot 64, it will fall out through the opening 68; and if something smaller than a dime is put in the slot 63, it will fall out through the opening 69. The passage 66 is downwardly bent as at 70. Slidably mounted adjacent the bottom of the passage 70 is a coin-moving member 71 adapted to receive a coin of any size that can pass through the passage portion 70 and to hold it upright as indicated in dotted lines. The coin mover or "escalator" 71 is secured to a member 72, which is itself slidably mounted upon a rod 73, carried at one end in an arm 74 formed as a part of the housing 62. At its other end, the rod 73 is supported on the member 75, which will be described below. As the coin is moved from the dotted line position to the position of the full line coin of Figure 2, it is carried under a gauge arm 76. This arm is pivoted as at 77 upon a support 78. It is slotted intermediate its ends as at 79. One end of a spring 80 is secured to the gauge arm 76. The other end of the spring is secured to a pin 81 upon a support or base member 82, which also carries the member 78. Mounted for vertical reciprocation in the base or housing 82 is a stop member 83. It is provided with an upwardly projecting arm 84, which carries a pin 85, positioned within the slot 79. The stop member 83 is provided, preferably on its lower edge, with a notch 86, which is the stop for "no discharge." It is provided with a notch 87, which is the stop for dimes, and with a notch 88, which is the stop for quarters. A portion 89 of the member 82 serves as the stop for half dollars. Formed also in the member 72 is a downwardly depending arm 90, within which the member 71 is positioned.

As a means for discharging the coins or tokens, the slide 52 carries a cam 91. The cam is arranged to contact a roller 92. The discharge mechanism also includes a shaft 93, which carries the roller 92, and is slidably mounted in a support 94, which may form a part of the base 1. At its lower end, the shaft 93 carries a head 95. A spring 96 is positioned about the shaft 93 and bears at one end against the head 95, and at the other against the base 1 or the member 94 or some suitable abutment. At its upper end, the shaft 93 carries a discharge member 97, which as shown particularly in Figure 3 has an arcuate portion 98. As shown in Figure 6, the arcuate portion is upwardly enlarged and extends upwardly above the portion 97. As shown in Figure 4, the arcuate enlarged portion 98 may extend into the cut-away parts 29 of the rounded coin pocket members 24 and 25. As a means for returning the slide 52 to its original position, a spring 99 is provided. At one end, the spring 70 is secured to a pin 100, which may be mounted on the base 1. At its other end, it is secured to a pin 101, secured to the slide 52. After a coin has been moved under the gauge arm 76 and tokens have been discharged, it is moved from that point and discharged through the

chute 102 in the member 75. Ordinarily, it will be discharged in a coin box or some place of safety, the details of which are not here shown. 103 is a guide for the discharge member 97 and 104 is a stop member formed on or attached to the pin 93 to limit its lower movement.

Although I have shown an operative form of my device, it will be understood that many changes in the form, shape and arrangement of parts might be made without departing from the spirit of my invention, and I wish that my showing be taken as in a sense diagrammatic.

The application is a continuation, in part, of my application Serial No. 58,911, filed January 13, 1936.

The use and operation of this invention are as follows:

With the parts as shown, the machine is ready to be operated. As shown in full lines in Figure 2, a dime X has been used and two tokens have been discharged. A half dollar has been inserted and lies in the "escalator" 71, as shown at Y. If the handle 55 is pulled to the right, it moves the slide 52, carrying the "escalator" to the right and first dislodges the coin X and causes it to drop through the chute 102. It then moves the coin Y under the gauge arm 76. Further movement of the handle does not move the "escalator" because the portion 72 strikes the portion 75 as a stop.

Since the half dollar is now in position under the gauge arm, it has raised the latter to its maximum height and has carried with it the stop member 83 to its maximum upper limit. When now further movement of the handle and slide to the right occurs, all of the notches 86, 87 and 88 being out of the path of the stop 60, the latter continues until it strikes the portion 89 of the member 82. During the first part of the movement in the slide, the lever 9 is not moved because the opening 61 in the slide is so much larger than the pin 43. A lost motion connection is thus provided to permit the discharge of the coin X and to permit, also, the positioning of the coin Y under the gauge arm and the movement of the gauge arm and the stop member. As the movement of the slide 52 continues after the member 72 has stopped, the lever 9 is now rotated and the dog 46 engaging a tooth of the rack 19 rotates it and the coin carrier. The amount of this rotation is limited by the contact of the stop 60 with one or another of the notches in the member 83. With the use of the maximum coin Y, as above mentioned, the stop 60 does not strike the notches but moves until it strikes the member 89, thus giving to the coin carrier its maximum rotation, and that rotation will in the present case have been enough to bring ten coin-carrying pockets with the tokens which they enclose into the discharge position.

After the maximum movement permitted by the stops has occurred, the handle 55 is released and the slide is returned by the spring 99 to its original position. The spring 58 assists during the initial part of this movement because it has also been compressed. As the slide reaches its position of rest or its initial position, the cam member 91 contacts the roller 92 and raises the member 93 which carries the discharge member 97 and 98, and, thus, moves that member from the full line position of Figure 4 to the dotted line position of that figure in which it is carried up into the cut-away portions 29 of the coin pocket-forming members 24 and 25; and it dislodges and discharges all coins or tokens which

it contacts. Since the carrier has moved to bring five pockets into discharge position, the five tokens or coins within those pockets will be discharged. The parts will remain stationary with the coin Y under the gauge arm 76 until another coin is inserted and the operation is repeated, the exact extent depending upon the size of the next coin to be inserted.

If the machine is operated when no coin is in it—that is to say, if the handle 55 is pulled and no coin has been inserted—there will be nothing present to hold the gauge arm 76 up and the stop 60 will contact the notch 86, and this will occur before the coin carrier has been rotated at all. Therefore, no coins or tokens will have been moved into the path of the discharge member and none will be discharged upon the release of the handle. Thus, the gauging and stop mechanism provides means for preventing unauthorized discharge of coins and for automatically discharging the proper number of coins.

I claim:

1. In combination in a mechanism of the class described, means for receiving, storing and discharging coins, said means comprising an operating slide, manual means for moving it in one direction and means for returning it to its original position, movable stop means for limiting the movement of said slide in one direction, stop positioning means operatively connected to said slide for positioning said stop during the initial movement of said slide towards said stop, a coin carrier associated with said slide and comprising an assembly having a coin carrying section formed to provide a plurality of coin receiving pockets, and carrier driving means to be moved by said slide and having carrier engaging means, means comprising a lost motion connection between said carrier driving means and said slide whereby said carrier remains stationary during the stop positioning movement of the slide, and means for discharging coins from said carrier.

2. A coin carrier comprising a body portion having a peripheral flange extending therefrom and above and below said portion, and a plurality of coin pocket defining members perpendicular to the plane of said body and secured to and projecting radially outwardly beyond said flange, said members each being provided with a cut-away portion extending inwardly from the underside thereof and adapted to receive a coin ejector, and each of said members being further provided with laterally directed coin supporting lugs positioned on opposite sides of said cut-away portion, the outer extremities of said pocket defining members being spaced to provide an outwardly opening discharge mouth for each of said pockets.

3. A coin carrier comprising a body portion, a peripheral flange on said body portion, and a plurality of coin pocket defining members perpendicular to the plane of said body and secured to said flange, said members being provided with cut-away portions extending inwardly from their lower edges and adapted to receive a coin ejector, downwardly inclined coin positioning lugs carried by each of said pocket defining members, each of said pocket defining members being provided with a laterally extending coin supporting lug, said coin supporting lug of each member being secured to an adjacent pocket defining member, and positioned between said cut-away portion and a radially outwardly directed coin discharge opening provided between adjacent pocket defining members.

4. A coin carrier comprising a plurality of plate-like members, each having a peripheral flange, the said flanges being aligned with each other, said plate-like members positioned together with the said flanges extending in opposite directions, and a plurality of coin pocket members perpendicular to the plane of said plate members and secured to said flanges and extending outwardly beyond them, said coin pocket members being formed in joined pairs, each pair having a plurality of integral lugs formed as an integral part of said pair, each lug secured to one of said flanges.

5. A coin carrier comprising a plurality of plate-like members, each having a peripheral flange, the said flanges being aligned with each other, said plate-like members positioned together with the said flanges extending in opposite directions, and a plurality of coin pocket members perpendicular to the plane of said plate members and secured to said flanges and extending outwardly beyond them, said coin pocket members being formed in joined pairs, each pair having a plurality of integral lugs formed as an integral part of said pair, each of said lugs secured to one of said flanges, each coin pocket member provided with a laterally bent lug adjacent its lower edge, said lug forming a stop to prevent coins falling through the bottom of a pocket.

6. A coin carrier comprising a plurality of plate-like members, each having a peripheral flange, said plate-like members positioned together with the flanges extending in opposite directions, and a plurality of coin pocket members secured to said flanges and extending outwardly beyond it, said coin pocket members being formed in pairs, each pair having a plurality of integral flange engaging lugs formed as an integral part of said pair, said lugs secured to said flanges, each pocket member provided with a cut-away portion adapted to allow the entrance of a coin discharge means, and an inwardly bent, coin-positioning lug adjacent each cut-away portion, said lugs projecting into the coin receiving space.

7. In combination in a coin-handling means, a supporting body member, a peripheral flange secured thereto, a plurality of pairs of coin pocket members perpendicular to the plane of said body member and secured to said flange, each of said pairs of members comprising two pocket-forming members and an integral portion joining them together, there being flange-engaging members on said joining portion secured to said flange, and laterally disposed lugs on said pocket-forming members, the lugs of each member being secured to those of an adjacent member.
